FERNAND LONGUEMARE AND GEORGES LONGUEMARE, OF PARIS, FRANCE,
ASSIGNORS TO AMÉLIE ADELÈ LONGUEMARE, OF PARIS, FRANCE.

CARBURETER FOR EXPLOSIVE-MOTORS.

SPECIFICATION forming part of Letters Patent No. 746,119, dated December 8, 1903.

Application filed October 13, 1902. Serial No. 127,047. (No model.)

To all whom it may concern:

Be it known that we, FERNAND LONGUEMARE and GEORGES LONGUEMARE, citizens of the Republic of France, residing at Paris, France, have invented certain new and useful Improvements in or Relating to Carbureters for Explosive-Motors and the Like, of which the following is a specification.

This invention relates to a carbureter for motors driven by an explosive mixture composed of hydrocarbon vapor and air and formed by the action of the suction of the motor in the carbureter, the supply of hydrocarbon being effected without special mechanism at a constant level and under any desired pressure, natural or artificial, the supply of mixture being controllable at will in the most precise manner and in any desired proportions.

The characteristic features of this carbureter consist, essentially, in the combination, with a distributing or supply pipe for the hydrocarbon arranged in a mixing-chamber, of an air-conduit surrounding said distribution pipe and projecting beyond it to a certain extent, so as to insure the intimate contact of the air drawn in with the stream of hydrocarbon distributed before the diffusion of the mixture in the chamber of the carbureter, the diffusion or intimate mixing being effected by the passage of the mixture through a grating constituted by a disk supported by the spindle or by the needle-valve spindle in the hydrocarbon-supply tube, the extent of rise of which is controllable at will by a conical or other abutment arranged horizontally above the upper end of this spindle and adapted to limit the upward movement of the spindle more or less, according as the cone is moved more or less into the path of the spindle, and thereby to effect at will and with great precision an absolutely exact and proportionate regulation of the hydrocarbon-supply to the distributing-pipe. This regulation of the hydrocarbon-feed is combined in the ordinary way with the admission of air for the formation of the explosive mixture in desired proportions.

In the accompanying drawings, Figure 1 shows a vertical section of a carbureter ac-

cording to the present invention. Fig. 2 is a cross-section on the line A B of Fig. 1.

The hydrocarbon-supply pipe or device *a*, with inclined or other spraying passages or holes *b*, is situated in the center of the mixing-chamber *c*. The latter is surrounded by a heating chamber or jacket *d*, heated by the circulation of the exhaust-gases flowing through the tubes *e f*. The part *a* is mounted upon the upper end of a vertical central tube *g*, into which hydrocarbon is introduced through a lower tube *h*, connected to it.

Concentrically arranged in the mixing-chamber *c* is a sleeve or tubular partition *i*, secured to the bottom of this chamber in any suitable manner. The base of the sleeve *i* is enlarged at *j*, so as to extend around the perforations *k* for the admission of air. The upper portion of the sleeve terminates in a cylindrical portion *l*, extending beyond the distribution device *a* and forming between its inner circumference and the tube *g* an annular space *m*, through which the air admitted through the passages *k* is drawn and brought in contact with the jets of hydrocarbon discharged through the passages *b* of the distributing device. The contact of the air and hydrocarbon before the diffusion of the mixture in the chamber *c* is sufficiently prolonged in order to effect immediately an intimate mixture by the extension of the cylindrical portion *l* of the sleeve *i*.

The tube *g*, as well as the distribution device *a*, surmounting the latter, are traversed in an axial vertical direction by a spindle *n*, with a pointed end *o* acting as a needle-valve in coöperation with an opening *p* for the admission of hydrocarbon to the distribution-chamber in the tube *g* and with which it forms an internal space connected with the device *a* and by radial passages with the spraying channels or perforations *b* in the latter. The spindle *n* carries at its end above the sleeve *i* a perforated disk *q*, which forms a grating. The mixture flowing through the upper part *l* of the sleeve *i* before it arrives at the supply-tube to the motor passes through the disk *q* in order to make the mixture of air and vapor as intimate as possible.

The chamber *c* is surmounted by a tubular

neck u for the admission of the mixture to the motor. This neck is at its rear part traversed diametrically by a rod with a wedge or cone r , terminating at one end in a rod s , seated in the corresponding wall of the tubular portion u , while the other end is formed with a screw t , which extends through the corresponding of the wall of the tube u and can be screwed in and out in order to vary the position of the cone r . This cone or abutment r is situated above the upper end of the spindle q of the needle-valve o , so that according to the transverse adjustment by the screw t it will present to the upper end of the spindle an abutment at a variable height, thereby limiting the vertical movement of the rod n , and thus controlling the opening of the supply-orifice p by the needle o , and consequently the distribution of the hydrocarbon to the chamber a . Finally, the tube u may be provided with supplementary air-admission ports v , regulated by a perforated ring x of known kind.

The operation of the apparatus is as follows: The tubular portion u being connected to the admission-tube of the motor and the pipe h to the hydrocarbon-supply pipe, the disk q is raised upon the suction of the piston in the motor-cylinder, and consequently also the spindle n , the needle-valve of which opens the orifice p , through which the hydrocarbon under a desired pressure flows into the supply-chamber of the distribution device a . There is thus produced a supply of air simultaneously drawn in through the orifices k with a supply of the hydrocarbon, which passes through the distribution-passages b of the part a . The air introduced through the orifices k into the enlarged portion j of the sleeve i passes through the restricted cylindrical portion l of the latter and comes into intimate contact with the jets of hydrocarbon discharged through the passages b , and this contact is continued during the flow through the cylindrical part l , thereby producing an initial and intimate mixture of the air with the hydrocarbon. This mixture encounters upon leaving the sleeve i the grating q above the latter, through which it is compelled to pass, whereby a thorough agitation and a complete mixing are obtained. The mixture then passes the tube u , and during its passage through the latter it can be modified at will by a supplementary admission of air effected through the ports v , under the control of the

annular regulator x . The spindle n upon being raised comes in contact with its upper end with the conical abutment r , the position of which has been previously adjusted by the screw t in such a manner that the extent of 60 rise of the spindle corresponds with that necessary for a desired supply of the hydrocarbon through the opening p . This regulation can be modified at will during the working of the motor to any desired extent by adjusting the 65 screw t in order to vary the height of the conical part r above the end of the spindle n . The closing of the opening p by the needle o is effected by the descent of the spindle n and the disk q upon the stoppage of the aspiration 70 by the motor. Therefore the weight of these parts should be greater than that corresponding to the feeding pressure of the hydrocarbon exerted upon the needle-valve o .

What we claim as our invention, and desire to secure by Letters Patent, is—

1. A carbureter for explosive-motors and the like comprising a combustible-charge-inlet pipe, an air inlet and mixing sleeve surrounding said pipe, said sleeve having an upper cylindrical portion which surrounds, in close proximity, the upper part of the charge-inlet device and extends beyond the same, a needle-valve having a perforated disk on the upper part of its spindle and coöperating with 85 a port to effect and control the supply of charge, and an adjustable conical abutment in the path of said spindle to limit the upward movement of the same substantially as described. 90

2. A carbureter for explosive-motors and the like comprising a combustible-charge-inlet pipe with outwardly-directed spraying-perforations in its upper part, a cylindro-conical air-inlet sleeve surrounding said pipe and 95 extending upward beyond it, a loose vertically-movable valve-spindle in said inlet-pipe a perforated disk on said spindle an adjustable conical abutment in the path of the valve-spindle, an inclosing casing and a heating-jacket surrounding the casing substantially as described. 100

In testimony whereof we have signed our names to this specification in the presence of two subscribing witnesses.

FERNAND LONGUEMARE.
GEORGES LONGUEMARE.
